[57] CLAIM

The ornamental design for a combined faucet and handshower holder, as shown and described.

DESCRIPTION

FIG. 1 is a perspective view taken from the top, front and left side of a combined faucet and handshower holder embodying my new design;

FIG. 2 is a right side elevational view thereof;

FIG. 3 is a top plan view thereof;

FIG. 4 is a left side elevational view thereof;

FIG. 5 is a front elevational view thereof; and,

FIG. 6 is a top plan view of a second embodiment thereof, which is the same as the first embodiment except that the handles and handshower holder are reversed.

The broken line representation of plumbing escutcheons in FIG. 1 is for purposes of illustration only and forms no part of the claimed design.
